UNITED STATES PATENT OFFICE.

MICHAEL STENTZ, OF ALBION, ASSIGNOR TO F. E. MYERS AND P. A. MYERS,
BOTH OF ASHLAND, OHIO.

HAY ELEVATOR AND CARRIER.

SPECIFICATION forming part of Letters Patent No. 281,726, dated July 24, 1883.

Application filed May 29, 1882. (No model.)

To all whom it may concern.

Be it known that I, MICHAEL STENTZ, a citizen of the United States, residing at Albion, in the county of Ashland and State of Ohio, have invented certain new and useful Improvements in Hay Elevators and Conveyers; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

15 The present invention relates to that class of devices for elevating and conveying hay or merchandise in barns or store-houses in which the load is conveyed onto an inclined track and caused to run by gravity to the place of 20 deposit.

The invention consists in connecting a hoisting-rope with the elevated end of an inclined stationary track passing over guide-pulleys in such a manner that when lowered the load of 25 hay or merchandise can be hung upon a wheeled carrier placed upon said rope. By raising or straightening the rope it is brought in line with the end of the stationary track and virtually forms a continuation thereof, and when 30 in this position the wheeled carrier passes onto the track and runs to the place of deposit by gravity, and the load is then dropped by a suitable tripping device. The carrier is then drawn back onto the rope and lowered for another load. Certain minor details of construction 35 also constitute part of my invention.

In the drawings, Figure 1 is a side elevation of my apparatus, showing the position of the parts when receiving the load. Fig. 2 is a side 40 elevation, showing the position of the parts when the load is passing onto the stationary track. Fig. 3 is a cross-section of the stationary track and end view of the hanger and carrier, and Figs. 4, 5, and 6 are detail views of 45 the device for connecting the elevating-rope with the stationary track.

The letter A designates an inclined track or rail formed of a round or angular bar, and secured at its lower or depressed end to a bracket or block, a, on the wall of the barn or store-house. The rail is secured to or supported

upon a hanger or frame, B, consisting of two or more angular bars, b, the upper ends of which have holes for the reception of hooks d on the rafter of the barn or store-house or 55 suitable supporting frame, as is shown in Figs. 1 and 2. One of the bars b is generally made longer than the other, so as to cause the rail A, secured thereto, to have the inclination already mentioned. The same result may, however, be attained by making the bars b equal in length, and providing suspension-hooks d differing in length. The vertical bars b may be connected by a horizontal bar or stretcher, e, and a hook or brace extending from the side 65 wall or suitable support on the barn engages with the track-supporting frame for properly strengthening the same. A rope, C, connected with the upper or elevated end of the rail A passes over a sheave or through a pulley-block, D, on the barn frame or support, and through a pulley-block, E, on the floor of the barn or warehouse. From thence the rope is carried out and connected with a draft-horse or a windlass, for the object hereinafter stated. 70 The rope is connected with the rail by means of a shoe, G, which is pivoted or fastened to the rail, and has a groove or seat for the reception of the rope, the latter being secured in place by means of rivets H, provided with 75 curved heads or end flanges, h. These rivets are passed through the rope and shoe and their ends riveted down, so as to cause the curved heads to overlap and clamp the rope in the manner fully shown in Fig. 4. 85

The carrier I, for receiving the load, consists of a bent bar, a sheave journaled therein, and a bottom hook for the attachment of a hay-fork or other device for grasping the load.

The operation of my apparatus is as follows, 90 viz: The stationary track having been secured in position within the barn or other place of deposit, the rope is slackened and the carrier lowered to receive the load, as is shown in Fig. 1. The rope is now hauled taut by a 95 draft-horse, windlass, or otherwise, as above explained, until the carrier is hoisted to the level of the upper end of the inclined track, and the rope forms a continuation of the same. The carrier then passes, with its load, onto the 100 rail, and the latter being inclined, it follows that the load runs down thereon by its weight

or gravity, and when the place of deposit is reached a rope, M, connected with the hay-fork is used for tripping the same and dropping the load. For repeating the above operations the elevating-rope is slackened and the carrier returned onto it by hauling it back with the trip-rope. A bell or audible signal is generally located at the junction of the rail and rope, to give notice when the load passes 10 onto the rail. This bell is struck by the carrier or by a proper arm attached thereto. The inclined track may be put up in any position within or outside of the barn or warehouse, wherever proper supports can be obtained for 15 the same and for the upper sheave, so as to receive the load at the most convenient point and deliver the same wherever desired. In operating the invention it is not necessary to let the carrier run to the end of the track before dropping the load, but the trip-cord can be pulled and the load dropped at any point on the track.

Having thus described my invention, what I claim as new, and desire to secure by Letters

25 Patent, is—

1. In an elevator and conveyer, and in combination, the stationary inclined rail or track, an elevating-rope connected to the raised end of said track and adapted to form a continuation thereof, proper guide-pulleys, and a load-carrier adapted to run on said rail or track, substantially as described.

2. In combination with the supported inclined rail or way of an elevator and conveyer, a pivoted hinged extension, an elevating-rope 35 attached to the free end of the extension, so as to form, when raised, a continuation of the track, suitable pulleys, and a load-carrier adapted to be hoisted and to run on the track or rail, all substantially as described. 40

3. In a hay or merchandise elevator and conveyer, the combination of the stationary inclined rail A and the elevating-rope C, connected with the raised end of said rail or track, and adapted to form a continuation thereof, 45 with a suitable rail-supporting frame, a traveling load-carrier adapted to run upon the rail, and rope and guide sheaves, as and for the purpose set forth.

4. The combination of the grooved or channeled shoe G and the hooked rivets and clamps H h with the track A, having the shoe pivoted thereto, and the rope C, seated in said shoe and secured thereto by the hooked clamps, as and for the purpose set forth. 55

In testimony whereof I affix my signature in presence of two witnesses.

MICHAEL STENTZ.
